US0D1106119S

(12) **United States Design Patent** (10) Patent No.: **US D1,106,119 S**
 (45) Date of Patent: ** Dec. 16, 2025

(54) **SPEAKER**

- (71) Applicant: **SONY GROUP CORPORATION**,
 Tokyo (JP)
- (72) Inventor: **Mazumi Osawa**, Kanagawa (JP)
- (73) Assignee: **SONY GROUP CORPORATION**,
 Tokyo (JP)
- (**) Term: **15 Years**
- (21) Appl. No.: **29/911,816**
- (22) Filed: **Sep. 8, 2023**

(30) **Foreign Application Priority Data**

(57) CLAIM

The ornamental design for a speaker as shown and described.

DESCRIPTION

FIG. 1 is a front, top, left perspective view of a speaker showing my new design;

FIG. 2 is a rear, bottom, right perspective view thereof, wherein the speaker is in a lying position;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrating portions of the speaker form no part of the claimed design.
